REFRIGERATING APPARATUS

John Ralph Fehr, Dayton, Ohio, assignor, by
mesne assignments, to General Motors Cor-
poration, a corporation of Delaware

Application May 30, 1933, Serial No. 673,720

17 Claims. (Cl. 62—4)

This invention relates to refrigerating apparatus and more particularly to mechanisms for defrosting or removing the frost from cooling units of refrigerating apparatus.

In the use of household refrigerator cabinets, it is customary to maintain the temperatures of the cooling unit below freezing to provide ice cubes and in some instances frozen comestibles as well as to cool the air within the refrigerator cabinet. The operation of the evaporator at a temperature below freezing, causes frost to collect upon the air cooling surfaces of the cooling unit. This frost acts as an insulator between the cooling unit and the ambient air and reduces the efficiency of the heat transfer between the air and the cooling unit.

This frost must be removed from the cooling unit or coil periodically and in the past this has been accomplished by merely discontinuing the operation of the refrigerating apparatus. While this method of removing frost is quite simple, it frequently happens that the user forgets to restore the apparatus, resulting in a prolonged absence of refrigeration.

The objects of my invention are to eliminate the objectionable features of former methods of defrosting by the provision of defrosting mechanism which will automatically restore the refrigerating apparatus to its normal operation after the defrosting is completed; and particularly a mechanism which may be operated as a fully automatic mechanism or a semi-automatic mechanism for defrosting.

It is a further object of my invention to incorporate such a defrosting mechanism into and with the temperature regulating mechanism so that all may be operated and controlled by the same operating member and so that the defrosting mechanisms are rendered ineffective when the temperature regulator is moved to provide colder than normal cooling unit temperatures.

It is another object of my invention to control all of these defrosting devices as well as the temperature regulator by a single manual control means and to so construct this manual control means so that only one of these devices will be effective at a time.

Further objects and advantages of the present invention will be apparent from the following description, reference being had to the accompanying drawings, wherein a preferred form of the present invention is clearly shown.

In the drawings:

Fig. 1 is a view of a refrigerating apparatus partly diagrammatic embodying my invention;

Fig. 2 is a top view of the control portion or means in Fig. 1;

Fig. 3 is an enlarged end view of the control means shown in Fig. 1; and

Fig. 4 is a sectional view along the line 4—4 of Fig. 3.

Referring to the drawings and more particularly to Fig. 1 there is shown a refrigerating system including a compressor 20 for compressing the refrigerant and forwarding the compressed refrigerant to a condenser 21 where the refrigerant is liquefied and collected in a receiver 22. From the receiver, the liquid refrigerant is forwarded through the supply conduit 23 to a float controlled flooded evaporator 24 which is located 15 within the food compartment 25 of a refrigerator cabinet 26. The cooling unit 24 absorbs heat from the air within the interior of the food compartment 25 causing the evaporation of liquid refrigerant, which evaporated refrigerant is returned to the compressor through the return conduit 27. The compressor 20 is driven by the electric motor 28 through suitable pulley and belt means 29. The electric motor 28 is provided with electrical supply conductors 30 and 31. 25

The temperature of the flooded type evaporating means 24 is controlled by a control means, generally designated by the reference character 32, which is in series with the electrical supply conductor 31 so as to control the operation of the electric motor. The control means 32 is connected to the return conduit 27 by a suitable tube 33 so that the control means operates according to the pressure within the evaporator 24, which pressure is proportional to the temperature of the evaporator. The control means 32 therefore controls the starting and stopping of the compressor according to the temperature and pressure of the evaporator 24. 35

Referring now particularly to the control means 32, there is provided a platform 35 upon which is mounted a metal bellows 36, the interior of which is connected to the tube 33. Above the bellows 36 is a lever 37 which is connected to the bellows 36 by a bellows follower 38. Surrounding the bellows 36 is a sort of a cage 39 which is supported by the platform 35 and which is provided with a bearing 40 which supports a pivot pin 41 for pivotally supporting the 45 end of the lever 37. The opposite end of the lever 37 is connected to a snap acting switch mechanism. This snap acting switch mechanism comprises a lever 42 which is pivotally mounted upon a pin 43 which is fixed to the 50

40

30

45

50

55

- main lever 37. This secondary lever 42 is made in two parts, one on either side of the lever 37 and these parts are connected together by suitable rivets 44 so that the two parts act as a unit.
- 5 At one end of this lever 42 there is provided a cam 45 which is riveted thereto and which is adapted to co-act with a spring pressed cam roller 46 mounted upon the upper end of a spring pressed lever 47 and pivoted at its lower 10 end upon a pin 48 which has its end mounted in an inverted U-shaped standard 49. The lever 47 is urged in a counter-clockwise direction about its pivot pin 48 by a spring 72 so that the roller 46 is resiliently held against the cam 45.
- 15 The standard 49 rests upon the platform member 35 and at its upper end carries a differential adjustment means 50 which contains a movable plunger 51 which is spring pressed against a shoulder within the differential adjustment 20 means. The lower end of this plunger 51 is adapted to engage the upper portion of the extreme end of the main lever 37 when this main lever end is in its upper position. However, when the main lever is moved to its lower position, the 25 shoulder within the differential adjustment means prevents the plunger from continuing to follow the main lever in its downward movement. In this way the lever 37 is only affected by the differential adjustment means at its upper limit 30 to provide a differential adjustment.
- A range adjustment means is also provided for the main lever 37. This range adjustment means comprises a vertical rod 55 which has its upper and lower ends threaded and which is 35 fastened at its upper end by means of a pin 56 to the main lever 37. The rod 55 of the range adjustment means passes through the platform 35 and is surrounded by a large spring 57 above the platform and a small spring 58 below the 40 platform. The tension of the spring 57 is controlled by a pair of nuts 59, one serving as an adjusting nut, and the other as a lock nut. Likewise, the tension of the spring 58 is controlled by a pair of nuts 60, one serving as an adjusting 45 nut and the other as a lock nut. By means of the tensioning of the springs 57 and 58, the pressure required within the bellows 36 in order to move the lever 37 in one direction or the other is controlled.
- 50 The end of the secondary lever 42 opposite the cam 45 is connected by a long pin 64 to an insulating link 65 which in turn is connected by means of a pin to a movable contact member 66. This movable contact member 66 is adapted to 55 cooperate with a stationary contact 67 mounted upon the platform 35. In order to guide the movement of the movable contact 66 this movable contact member is connected by means of copper strips 68 which are pivoted at their opposite end to an insulating member 69 which is mounted 60 beneath an aperture 70 in the platform 35. One portion of the electrical supply conductor 37 is connected to one of the copper strips 68 while the other portion is connected to the stationary contact 67.
- 65 By means of this mechanism, as the temperature and pressure within the cooling unit 24 rises, the bellows 36 expands under control of the springs 57 and 58 so that the free end of the main lever 37 moves upwardly and contacts the 70 lower end of the plunger 51 forming a part of the differential adjustment means. As the main lever 37 continues its upward movement, the plunger 51 is moved upwardly against the tension of its own spring member and finally the cam 45

is moved upwardly from a position beneath the cam roller 46 to a position above the roller so that the secondary lever 42 is caused to turn counterclockwise about its pivot pin 43 to move the movable contact 66 into contact with the stationary contact 67. This closes the circuit to the electric motor 28 and starts the operation of the compressor 20. The operation of the compressor 20 removes the vapor from the cooling unit 24 and condenses this vapor in the condenser 21. This in turn causes the pressure within the return conduit 27 to be lowered and this lowering of the compressor tends to contract the bellows 36 against the tension of the range adjusting springs 57 and 58. The main 15 lever 37 moves downwardly because of the contraction of the bellows 36 and causes the cam 45 to move from the position above the cam roller 56 to a position below the cam roller 46. This cam roller 46, is, of course, pressed against the 20 surface of the cam 45 by the spring 72 which urges the cam roller lever 47 in the counterclockwise direction about the pivot pin 48. The urging of the cam roller against the upper face of the cam 45 causes the lever 42 to move in a 25 clockwise direction about its pivot pin 43 to open the switch contacts 66 and 67.

In order to provide lower temperatures of the evaporator 24 for freezing purposes, there is provided a temperature regulator. This temperature regulator is mounted upon an L-shaped bracket member 75 which has its lower horizontal portion fastened beneath the platform 35. The upper vertical portion is provided with a dial 76 and a rotatable handle 77 which is fixed 30 upon the end of a shaft 78 rotatably mounted in the vertical portion of the L-shaped bracket 75. The shaft 78 extends a considerable distance back of the vertical portion of the L-shaped bracket 75 and has a temperature regulating 35 spring 79 having a portion coiled thereabout. The forward end of this coil portion extends into a slot 81 which extends through the greater portion of the shaft 78. Extending from the other end of the coil portion of the spring is a 40 straight portion which is adapted to engage, when moved into position, an extension of the pivot pin 43. When this straight end portion of the temperature regulating spring is moved 45 into contact with the pivot pin 43 it assists the bellows in moving the switch to closed circuit position and thus causes the electric motor to operate for longer periods of time so as to reduce the average temperature of the evaporator 24 below normal. The handle 77 is provided 50 with an engaging pin beneath its knob which is adapted to engage apertures 82 extending around the outer portion of the dial 76. Some of these apertures are designated 1, 2, 3, 4, and 5 which 55 designate the various temperature regulating 60 positions. When the handle 77 is moved to number 1 position, the free end of the temperature regulating spring 79 engages the pivot pin 43 to apply pressure thereon in order to urge it upwardly with a certain tension. When the handle 65 77 is moved to number 2 position, an increased tension or pressure is applied to the pin 43, while when the handle is moved to position 3, 4, and 5, an increased pressure or tension upon the pin 43 is made in each case. Thus, by this device the temperature of the cooling unit 24 may be lowered at any time below the normal average temperature in five different degrees, any 70 of which may be selected.

As stated in the beginning of the specification, 75

the evaporator 24 is normally maintained below freezing temperatures. This causes frost to accumulate upon the surface of the evaporator and this frost acts as a sort of an insulator. By 5 acting as an insulator, the efficiency of heat transfer is reduced between the air in the cabinet and the liquid refrigerant within the cooling unit 24. This also lowers the entire operating efficiency of the refrigerating system. In order to 10 maintain a reasonable operating efficiency it is therefore necessary to remove this frost from the cooling unit whenever it builds up to a substantial amount. The most convenient way of doing this is to permit the temperature of the evaporator 15 to rise above the freezing temperature and thus cause the frost to melt from the cooling unit. However, this is not without objectionable features. The increase of the temperature of the evaporator of the cooling unit 24 above freezing 20 temperatures causes the temperature to be increased within the cooling compartment 25 and thus increases the danger of food spoilage; hence when there is a large amount of food within the cabinet which might be damaged by the increase 25 in temperature, it is undesirable to have any defrosting at such a time. For this reason, it is often desirable to wait until the food supply within the refrigerator is low before defrosting is attempted. The increase of the temperature 30 of the evaporator above the freezing point also delays or prevents the freezing of ice cubes, desserts, and other comestibles within the evaporator or cooling unit 24. This increase in temperature may also cause the melting of any ice 35 cubes which may be in the evaporator during a defrosting period. Some of the other objections to this defrosting have been that the housewife does not defrost her cooling unit regularly enough or often enough and also that sometimes 40 she begins a defrosting period and then forgets to terminate this defrosting period at the proper time when the cooling unit has been completely defrosted.

In the past it has been customary to defrost 45 the cooling unit or evaporator by the shutting off of the refrigerating apparatus for a period of time sufficient to raise the temperature of the evaporator above freezing for a long enough time to cause the frost to completely melt from the cooling unit. Thereafter it was necessary to 50 again restart the apparatus. While this arrangement was fairly satisfactory in that it permitted the defrosting of the refrigerator at any time desired by the housewife and for any period desired by her, it was found that this defrosting 55 was not performed often enough or regularly enough and that the defrosting periods were often made too long and the food compartment denied refrigeration for too great a time. In order to overcome these difficulties, I provide 60 automatic means for performing this defrosting which will insure that the apparatus will be restored at the proper time. In one type of such automatic means, the defrosting period is manually initiated, that is, the housewife is required 65 to set the defrosting mechanism whenever she desires a defrosting period to occur, but mechanism is provided for terminating such a defrosting period automatically after the cooling unit reached a certain temperature which ordinarily 70 insures complete defrosting. The automatic means also provides defrosting cycles completely automatically at periodic intervals, if desired. Each of these forms serves excellently at certain 75 times if properly attended to. At other times

these devices are objectionable. For instance, when there is provided a completely automatic defrosting device which provides periodic defrosting cycles automatically, a defrosting cycle may occur when it is desired to freeze ice cubes 5 or when there is a large amount of food within the refrigerator cabinet which is likely to be spoiled by such defrosting. With the other type of automatic defrosting, which is sometimes called semi-automatic, defrosting may not be 10 performed sufficiently often and the length of defrosting period may not be sufficient if defrosting has not been attended to for a great length of time. Thus, it will be seen that there are objectionable features to each type of de- 15 frosting but there also seems to be a place for each of these types of defrosting.

I therefore provide in my control means a provision for each of these types of defrosting means, and, further, so combine these defrosting means 20 with the temperature regulator so that all may be controlled by the handle 77 and further correlate these devices by means of a regulating cam so that only one will be effective at a time. Thus when the handle 77 is in any one of the cold control 25 positions, no defrosting will occur. When the regulating handle 77 is in full automatic defrosting position, only the periodic automatic defrosting cycles will occur. When the regulating handle 77 is in semi-automatic position, only the 30 semi-automatic defrosting period will occur. While, if the handle 77 is moved to full defrost or off position, the operation of the refrigerating apparatus will be stopped until such time as the regulating handle 77 is moved to one of the other 35 positions.

In order to provide a means for performing a fully manual defrost, that is, by shutting off the refrigerating apparatus, I provide a sheet metal arm 90 which is keyed to the regulating shaft 78. 40 This arm is substantially in alignment with the regulating handle 77 and when the regulating handle 77 is moved clockwise to the off position, the end of this arm 90 engages the projecting end of the pin 64 so as to forcibly move the switch contact 66 to open position and to hold it there as long as the regulating handle 77 remains in this position. This arm 90 therefore serves to lock the switch in open position.

In order to provide means periodically defrosting the cooling unit, I provide a ratchet wheel 100 50 slidably and rotatably mounted upon the pivot pin 43. This ratchet wheel is, of course, moved up and down by the movements of the main lever 37. Positioned in the path of movement of the 55 ratchet wheel 100 is a spring pressed pawl 101 which is pivoted upon the pin 48 and which is urged against the stop pin 102 by a spring 103. Therefore when the ratchet wheel 100 is moved downwardly by the main lever 37 it will engage 60 the pawl 101 and be rotated a distance of one tooth. This rotation of the ratchet wheel 100 is controlled by an aligning detent spring 104 which resiliently engages the teeth of the ratchet wheel. This spring which is in the form of a leaf spring 65 is riveted to the main lever 37.

The ratchet wheel 100 carries a pin 105 near its periphery, which pin projects from opposite sides of the ratchet wheel. This pin 105, is, of course, moved step by step or tooth by tooth, 70 about the pin 43 just as is the ratchet wheel 100. In order to periodically increase the temperature of the cooling unit automatically, I cause this pin 105 to periodically engage a prong 106 which forms a part of the forked end of an arm 107 75

which is pivoted upon the pin 41 which also serves as a pivot pin for the main lever 37. This arm 107 is pulled downwardly by a tension spring 108 which is hooked at its lower end to an eye screw 109 threaded into the platforms 35 and provided with a lock nut 110. The upper end of the spring 108 is hooked on to an eye screw 111 which passes through a passage 112 provided in the arm 107. Resting on the upper face of the arm 107 is an adjusting nut 113 which is threaded upon the eye screw 111 and is provided with a lock nut 114. In order to prevent the spring 108 from pulling the arm downwardly too far and to prevent it from coming into engagement with the teeth of the ratchet wheel 100, there is a stop 105 upon the cage 39 of the bellows which engages the bottom of the arm 107 to limit its downward movement.

As stated before, the ratchet wheel 100 is slidably and rotatably mounted upon the pivot pin 43. In order to control the lateral movement of the ratchet wheel 100, there is provided a fork 120, the prongs of which are turned inwardly to engage the sides of the ratchet wheel. These prongs remain between the center of the ratchet wheel and the path of movement of the pin 105 so that there is no interference between the prongs of the fork 120 and the pin 105. The fork 120 is pivoted at its lower end to an ear 121 which is turned out from the inverted U-shaped standard 49. This fork is also connected to a slide bar 122 provided with a forked projection 123 extending upwardly at an angle of about 45°. The movement of the slide bar 122 is controlled by the pin 124 mounted in the ear 125 extending from the standard 49. This pin 124 extends into a slotted aperture 125 formed in the slide bar 122. The forked end of the projection 123 engages a regulating cam 128 mounted upon the end of the regulating shaft 78. This regulating cam is in the form of a disc whose periphery extends into the notch which forms the forked end of the projection 123. The periphery of this cam 128 is warped or bent laterally toward the dial 76 to form a nose 129. When the cam 128 is rotated by the handle 77 the nose enters into the notch formed in the end of the projection 123 and moves the slide 122 toward the dial 76 to pivot the fork 120 counterclockwise in order to move the ratchet wheel toward the dial 76. By moving the ratchet wheel towards the dial 76, the pin 105 is caused to move directly beneath the projecting prong 106 at the end of the arm 107 in a generally elliptical path. Should this pin 105 and the prong 106 be in exact alignment when this shifting of the ratchet wheel is made, the pin 105 will cam the prong 106 and the arm 107 upwardly by reason of the inclined surface 103 which is provided on the inner side of the prong 106. Thus, the prong will be lifted on top of the pin 105.

When the ratchet wheel is in this position, it is rotated as usual step by step, that is, tooth by tooth, by the pawl 101. It also reciprocates as usual with the main lever arm 37. This indexing takes place when the lever 37 is moved to its lower position and once every revolution of the ratchet wheel 100, the pin 105 is indexed to a position directly beneath the prong 106. On the next upward movement of the lever 37, the top of the pin 105 comes into engagement with the lower flat surface prong 106 and this imposes an additional burden upon the main lever 37 so as to increase the pressure required within the bellows 36 to move the switch to closed circuit position. 75 This increase in burden is caused for the reason

that the pin 105 is required to lift the arm 107 against the tension of the spring 108. This increase in pressure required in the bellows to cause the switch to move to closed circuit position delays the starting of the refrigerating apparatus for the next running period and thus causes the temperature of the evaporator to rise above the freezing point. The tension of the spring 108 is so adjusted by the nut 113 that the pressure required to close the switch at this time 10 is one which corresponds to a temperature within the evaporator of several degrees above freezing, for example, about 34 to 36° F.

This mechanism provides a periodic defrosting cycle each time the pin is moved into position 15 beneath the prong 106 or, in other words, once every revolution of the ratchet wheel 100. This occurs entirely automatically so long as the handle 77 remains in full automatic position. However, as soon as the handle 77 is moved to one of 20 the other positions on the dial the regulating cam 128 moves the ratchet wheel and the pin 105 away from the prong 106.

In order to provide the other form of automatic defrost, which is sometimes called semi-automatic defrosting, the ratchet wheel is moved in the opposite direction from its central position (shown in Fig. 3). When in this position the opposite end of the pin 105 is caused to engage the other prong 135 which forms the other 30 part of the forked end of the arm 107. This other prong has a somewhat more complex structure than the prong 106. This prong 135 has a cam or inclined surface 136 on its inner face which when engaged by the end of the pin 105 35 in its lateral movement when in alignment therewith causes the lifting of the arm 107. Adjacent this inclined surface 136 and directly opposite the prong 106 there is a shoulder 137 which forms a resting place for the pin 105. At the side of 40 this shoulder there is provided a vertical circuit 138 which acts as a guide and a stop to limit the movement of the pin and the ratchet wheel away from the dial 76. It is desired that when in this position there will be provided a plurality of defrosting cycles, that is, cycles in which during a portion of the time, the temperature of the cooling unit will be raised about the freezing point and after the termination of a predetermined number of these defrosting cycles that the periods 50 be restored to normal operation. In order to do this, another cam surface 139 is provided at the rear of the guiding surface 138. This cam surface 139 is adapted when the ratchet wheel is indexed a predetermined number of times to 55 move the ratchet wheel to its central position. When moving the ratchet wheel to its central or neutral position, the fork 120 is also moved thereby moving the slide bar 122 and the projecting arm 130 forming part of the slide bar 122 acts 60 against the semi-automatic defrosting nose 141 upon the periphery of the cam 128 in order to cause the cam to be rotated and also the handle 77 to neutral position designated by "N". In the semi-automatic position, there is no aperture provided to detain the regulating handle 77 in that position but merely a slight depression which may be overcome by the cam surface 139 upon the prong 135 which moves the ratchet wheel to neutral position. When the regulating handle is 70 thus moved to neutral position the switch means is again set for operation without any defrosting or colder temperature regulation until the handle 77 is reset.

It will thus be seen that I have provided a re- 75

frigerating apparatus with a control means providing for suitable temperature regulation for freezing purposes, as well as three different defrosting mechanisms, each of which is individually controlled by a single regulating handle which also serves as an indicator and this handle, together with the cam 128 so correlates these devices so that only one is effective at a time.

While the form of embodiment of the invention as herein disclosed, constitutes a preferred form, it is to be understood that other forms might be adopted, all coming within the scope of the claims which follow.

What is claimed is as follows:

1. Refrigerating apparatus including a refrigerant liquefying means and a refrigerant evaporating means, means for cyclically controlling the apparatus for maintaining the evaporating means at a normal average temperature, means responsive to the cyclical operation of the apparatus for automatically, at predetermined intervals, increasing the average temperature of the evaporating means above the normal average temperature for providing periodic defrosting cycles, manually initiated means operable at will for providing defrosting cycles, said last mentioned means including automatic means for restoring the apparatus to the normal control of said control means.

2. Refrigerating apparatus including a refrigerant liquefying means and a refrigerant evaporating means, means for controlling the apparatus for maintaining the evaporating means at a normal average temperature, means for automatically, at predetermined intervals, increasing the average temperature of the evaporating means above the normal average temperature for providing periodic defrosting cycles, manually initiated means operable at will for providing defrosting cycles, and means operated by the change in temperature in the apparatus during a defrosting cycle for terminating a defrosting cycle.

3. Refrigerating apparatus including a refrigerant liquefying means and a refrigerant evaporating means, means for cyclically controlling the apparatus for maintaining the evaporating means at a normal average temperature, means for automatically, at predetermined intervals, increasing the average temperature of the evaporating means above the normal average temperature for providing periodic defrosting cycles, manually initiated means operable at will for temporarily varying from normal the temperature of the evaporating means for a plurality of cycles for providing a plurality of altered cycles and thereafter automatically returning the apparatus to normal operation.

4. Refrigerating apparatus including a refrigerant liquefying means and a refrigerant evaporating means, means for cyclically controlling the apparatus for maintaining the evaporating means at a normal average temperature, means for automatically, at predetermined intervals, increasing the average temperature of the evaporating means above the normal average temperature for providing periodic defrosting cycles, manually initiated means operable at will for temporarily increasing the temperature of the evaporating means for providing a plurality of defrosting cycles and thereafter automatically returning the apparatus to normal operation, said manually initiated means rendering said periodic means inoperative for succeeding cycles.

5. Refrigerating apparatus including a refrigerant liquefying means and a refrigerant evap-

orating means, means for controlling the apparatus for maintaining the evaporating means at a normal average temperature, automatic means for periodically increasing the average temperature of the evaporating means above the normal average temperature for providing periodic defrosting cycles, manually initiated means operable at will for temporarily increasing the temperature of the evaporating means for providing defrosting cycles and thereafter automatically returning the apparatus to normal operation, and selectively operable common means for selectively controlling the periodic means and said manually initiated means.

6. Refrigerating apparatus including a refrigerant liquefying means and a refrigerant evaporating means, means for controlling the apparatus for maintaining the evaporating means at a normal average temperature, automatic means for periodically increasing the average temperature of the evaporating means above the normal average temperature for providing periodic defrosting cycles, manually initiated means operable at will for temporarily increasing the temperature of the evaporating means for providing defrosting cycles and thereafter automatically returning the apparatus to normal operation, and common selective means for controlling the periodic means and the means operable at will so that only one will be effective at a time. 30

7. Refrigerating apparatus including a refrigerant liquefying means and a refrigerant evaporating means, means for controlling the apparatus for maintaining the evaporating means at a normal average temperature, automatic means for periodically increasing the average temperature of the evaporating means above the normal average temperature for providing periodic defrosting, a first means operable at will for temporarily lowering the temperature of the evaporating means below the normal average temperature for freezing purposes, a second means operable at will for providing defrosting cycles and thereafter automatically returning the apparatus to normal operation, and common means 45 for controlling the first and the second means operable at will.

8. Refrigerating apparatus including a refrigerant liquefying means and a refrigerant evaporating means, means for controlling the apparatus for maintaining the evaporating means at a normal average temperature, automatic means for periodically increasing the average temperature of the evaporating means above the normal average temperature for providing periodic defrosting, a first means operable at will for temporarily lowering the temperature of the evaporating means below the normal average temperature for freezing purposes, a second means operable at will for providing defrosting cycles 60 and thereafter automatically returning the apparatus to normal operation, and common means for controlling the periodic means and the first and second means operable at will. 55

9. Refrigerating apparatus including a refrigerant liquefying means and a refrigerant evaporating means, means for controlling the apparatus for maintaining the evaporating means at a normal average temperature, automatic means for periodically increasing the average temperature of the evaporating means above the normal average temperature for providing periodic defrosting, a first means operable at will for temporarily lowering the temperature of the evaporating means below the normal average tem- 75

perature for freezing purposes, a second means operable at will for providing defrosting cycles and thereafter automatically returning the apparatus to normal operation, and common means for controlling the first and the second means operable at will so that only one will be effective at a time.

10. Refrigerating apparatus including a refrigerant liquefying means and a refrigerant evaporating means, means for controlling the apparatus for maintaining the evaporating means at a normal average temperature, automatic means for periodically increasing the average temperature of the evaporating means above the normal average temperature for providing periodic defrosting, a first means operable at will for temporarily lowering the temperature of the evaporating means below the normal average temperature for freezing purposes, a second means operable at will for providing defrosting cycles and thereafter automatically returning the apparatus to normal operation, and common means for controlling the periodic means and the first and second means operable at will so that only one will be effective at a time.

11. Refrigerating apparatus including a refrigerant liquefying means and a refrigerant evaporating means, means for controlling the apparatus for normally maintaining the evaporating means at a normal average temperature, a first means operable at will for temporarily increasing the temperature of the evaporating means to provide defrosting cycles and thereafter automatically returning the apparatus to normal operation, a second means operable at will for shutting off the apparatus, and selective common means for selectively controlling the first means and the second means.

12. Refrigerating apparatus including a refrigerant liquefying means and a refrigerant evaporating means, means for controlling the apparatus for maintaining the evaporating means at a normal average temperature, a first means operable at will for temporarily increasing the temperature of the evaporating means to provide defrosting cycles and thereafter automatically returning the apparatus to normal operation, a second mass operable at will for shutting off the apparatus, a third means operable at will for temporarily lowering the temperature of the evaporating means for freezing purposes, and common means for controlling the first means, the second means, and the third means.

13. Refrigerating apparatus including a refrigerant evaporating means and a refrigerant liquefying means, control means for controlling the liquefying means to maintain a normal average temperature of the evaporating means by intermittently operating the liquefying means to provide cycles composed of an operating period and an idle period so that the temperature of the evaporating means is lowered to a predetermined normal low temperature limit during one portion of the cycle and raised to a normal predetermined high temperature limit during another portion of the cycle, each being below the freezing point, means operable at will for altering the operation of the control means to raise the high temperature limit above the freezing

point for each successive cycle for a predetermined number of cycles for defrosting purposes and thereafter automatically returning the refrigerating apparatus including the control means to normal operation.

5

14. Refrigerating apparatus including a refrigerant evaporating means and a refrigerant liquefying means, control means for controlling the liquefying means to maintain a normal average temperature of the cooling unit by intermittently operating the liquefying means to provide cycles composed of an operating period and an idle period so that the temperature of the evaporating means is lowered to a predetermined normal low temperature limit during one portion of the cycle and raised to a normal predetermined high temperature limit during another portion of the cycle, means operable at will for altering the operation of the control means to raise the average temperature of the evaporating means for a predetermined number of successive cycles for defrosting purposes and thereafter returning the refrigerating apparatus including the control means to normal operation.

25

15. Refrigerating apparatus including a refrigerant liquefying means and a refrigerant evaporating means, cyclical control means for starting and stopping the refrigerant liquefying means for maintaining said evaporating means at freezing temperatures at which frost collects thereon, and manually initiated defrosting means operable at will for temporarily increasing the temperature of the evaporating means above ice freezing temperature for a plurality of successive cycles to melt frost from the evaporating means and thereafter automatically returning the apparatus to normal operation.

30

16. Refrigerating apparatus including refrigerant liquefying means and a refrigerant evaporating means, means for controlling the apparatus for maintaining the evaporating means at freezing temperatures, means for automatically at predetermined intervals increasing the temperature of the evaporating means above freezing temperatures for providing periodic defrosting cycles, manually initiated means operable at will for temporarily increasing the temperature of the evaporating means above ice freezing temperatures, and thereafter automatically returning the apparatus to normal operation, said manually initiated means including means for rendering the periodic means inoperative for succeeding cycles.

45

17. Refrigerating apparatus including a refrigerant liquefying means and a refrigerant evaporating means, pressure operated means for controlling the apparatus for normally maintaining the evaporating means at a normal average temperature, an abutment means, an engaging means carried by said pressure operated means, means for periodically bringing said engaging means into alignment with the abutment means to periodically vary the temperature of the evaporating means, and means for holding said engaging means out of alignment and preventing the effective operation of the periodic means.
